UNITED STATES PATENT OFFICE.

FRANK C. MARQUARDT, OF BROOKLYN, NEW YORK, ASSIGNOR TO AMERICAN BANK NOTE COMPANY, OF NEW YORK, N. Y., A CORPORATION OF NEW YORK.

PRINTING MACHINE.

Application filed March 8, 1922. Serial No. 541,896.

To all whom it may concern:

Be it known that I, FRANK C. MARQUARDT, a citizen of the United States, residing at the borough of Brooklyn, in the city of New York, county of Kings, and State of New York, have invented certain new and useful Improvements in Printing Machines, of which the following is a specification, reference being had therein to the accompanying drawings, which form a part thereof.

My invention relates to printing machines, and more particularly to the plate cylinder construction of a multicolor printing machine of a type adapted to produce an imprint in a plurality of colors upon a single impression.

In machines of the type to which my invention relates, a plurality of form or plate cylinders each having associated therewith its own inking mechanism, are grouped about a planographic cylinder having an offset printing surface or surfaces, the plates upon each of said plate cylinders being adapted, with each rotation of said impression cylinder, to transfer complementary portions of a complete design in different colors to the planographic surface or surfaces thereon. Said planographic cylinder has associated therewith an impression cylinder, so that with each rotation of the planographic cylinder, the completed design in different colors is impressed upon the sheet being fed. By this construction, which broadly considered forms no part of my present invention, absolute register of all portions of the design in different colors is assured and absolute identity in different impressions is secured, since register of the different color plates is dependent upon mechanisms in the machine and not upon accuracy in the feed of the sheet with relation to the printing couple.

In the construction of machines of the type above referred to, as heretofore used, absolute register of different portions of the design made at a single impression, has been possible, but in non-perfected work great difficulty has been experienced in securing sufficiently accurate register of a design upon one side of the sheet with the design upon the reverse side, particularly when the plates used upon the machine have considerable width and bear repetitions of the same design.

The difficulty of securing register of the designs upon the front and the back of a sheet, which heretofore had been believed to be insurmountable, results from the fact that a plurality of designs, each of which is a duplicate of the other, has been produced upon a plate of zinc, aluminum, or other similar material used in making photo engraved plates, it being necessary to impress each design upon the plate photographically prior to the acid etching of the plate. A large number of such designs are ordinarily produced upon each plate, which is fairly wide, and while little difficulty has been experienced in accurately positioning in lateral and longitudinal alignment, the designs upon a plate for making an imprint on one side of a sheet, when making the plate for the reverse side of the sheet, it was necessary to secure register of the designs upon opposite sides of a sheet, that the designs upon the last named plate be placed identically with the designs upon the plate from which the other side of the sheet was printed, since no adjustment of the machine was provided for, which could correct slight imperfections due to the improper placing of the designs upon the different printing plates.

To correct the above conditions, I so construct the printing press that the plate cylinder is adapted to receive two plates, one of which is adapted to have thereon a plurality of similar designs or portions of designs, to be impressed upon one side of the sheet, and the other of which is adapted to receive a plate having formed thereon a plurality of similar designs or portions of designs for the reverse side of the sheet, said plates being capable of registering adjustment with relation to each other so as to bring the designs upon the different plates in absolute register one with the other. In this manner a sheet upon one impression will receive upon one-half thereof, imprints for the front of the completed design, while upon the other half thereof it will receive imprints for the reverse side of the sheet, so that by merely turning the sheet upon the succeeding impression, the portion of the sheet having the front design thereon will have the back or reverse design impressed thereon in exact register with the front design and the portion of the sheet having the back design thereon will have impressed thereon the

front design in exact register with the back design.

Since the relation of the different designs for the front of the sheet and for the back 5 of the sheet is determined by the mechanisms of the machine, it is apparent that absolute register of the designs upon opposite sides of the sheet is assured.

In securing the desired result, I provide a 10 plate cylinder consisting of a plurality of sections, one section being capable of adjustment both axially and circumferentially of the cylinder entirely independently of the other, so as to permit relative registering 15 adjustment of the plates carried by the different sections.

While said sections are capable of independent adjustment as described, the construction is such that when register of the 20 different plates is once secured, the cylinder in its entirety may be adjusted circumferentially or axially thereof to secure register of the designs or portions of designs upon the respective plates, with designs or 25 portions of designs upon plates upon different plate cylinders without disturbing the adjustment of the different sections upon each cylinder. This condition is particularly desirable with printing machines of the 30 multicolor type employing a plurality of plate cylinders, since during the makeready of a press it is not only essential that the different plates upon each cylinder be brought in accurate relation with each other, 35 but that the plates upon each cylinder may be brought into register with the plates upon other cylinders.

The invention consists primarily in a printing machine embodying therein a plate 40 cylinder having a plurality of independently movable sections, means carried by each of said sections whereby a plate may be secured thereto, co-operating members carried by and connecting adjacent sections to cause 45 them to rotate in unison, one of said members including therein means whereby it may be actuated to impart to one of said sections circumferential movement in relation to the adjoining section to cause said section 50 to be adjusted circumferentially of the axis of the cylinder entirely independently of another, and means whereby all of said sections may be simultaneously rotated; and in such other novel features of construction 55 and combination of parts as are hereinafter set forth and described, and more particularly pointed out in the claims hereto appended.

Referring to the drawings, 60 Fig. 1 is a diagrammatic view of a multi-color printing machine to which my invention is particularly adaptable;

Fig. 2 is a side view partly broken away, 65 of one of the plate cylinders of a printing machine;

Fig. 3 is a plan view of the construction shown in Fig. 2;

Fig. 4 is a section on the line 4—4 of Fig. 2;

Fig. 5 is a section on the line 5—5 of 70 Fig. 2;

Fig. 6 is a section on the line 6—6 of Fig. 2; and

Fig. 7 is a section on the line 7—7 of Fig. 2. 75

Like numerals refer to like parts throughout the several views.

In the embodiment of my invention shown in the accompanying drawings, I have illustrated diagrammatically in Fig. 1, an 80 embodiment of my invention employing a single printing couple consisting of an offset planographic cylinder 10 having associated therewith an offset planographic impression cylinder 11. Grouped about the cylinder 10 are four plate cylinders 12, 13, 14 and 15, each having associated therewith an inking mechanism including a plurality of ink founts so as to permit the application of inks 85 in a plurality of colors to the plates upon 90 each cylinder when desired.

The inking mechanism associated with the plate cylinder 12 is indicated at A and the ink founts associated therewith at A' and A'', respectively, and the inking and distributing rollers by which ink received from said founts is worked and applied to the plates upon said cylinder 12, at A³.

The inking mechanism associated with the plate cylinder 13 is indicated at B, the plates upon said cylinder being served by three ink founts B', B'' and B³ through the medium of the distributing and inking rollers B⁴.

The inking mechanism associated with the cylinder 14 is indicated at C, which mechanism includes three ink founts C', C'' and C³ and the distributing and inking rollers C⁴.

The plate cylinder 15 has associated therewith an inking mechanism D including 110 therein the ink founts D' and D'' and distributing and inking rollers D³.

The impression cylinder 11 has associated therewith a plate cylinder 16, inked through the medium of an inking mechanism E which includes the ink founts E' and E'' and the distributing and inking rollers E³. The cylinder 16 and its associated inking mechanism E is provided so as to permit a portion of a design in ink to be applied directly to the cylinder 11 if it be desired to use the machine in semiperfecting work, or when it is desired to increase the range of color work, or have a portion of the design duplicated upon both sides of a printed sheet.

In the type of machine shown in Fig. 1, the cylinder 10 is provided with a plurality of blankets so as to be capable of making two impressions with each rotation of said 130

cylinder, the impression cylinder 11 having two revolutions with each full revolution of the cylinder 10.

While the adjustments of the machine are such that the plates upon all of the cylinders 12 to 15 may be used to apply an inked design to either of the blankets upon the cylinder 10; or the plates upon some of said cylinders may be used with one of said offset surfaces on the cylinder 10, and the plates upon other of said cylinders may be used with the other surface, so that if desired, the inked design upon one of said surfaces may be transferred to the cylinder 11, these particular characteristics of the machine are immaterial to my present invention, which relates more particularly to the construction of the various plate cylinders by which a plurality of independent plates may be used upon each of said cylinders and the designs upon said plates as to each cylinder may be brought into register one with the other entirely independently of the other plate cylinders, the construction being such, however, that after register of different plates upon said cylinder has been secured, the plates thereon may be brought into register with plates upon different cylinders without disturbing the registering relation of the plates upon the same cylinder.

Since the construction of each plate cylinder 12 to 16 is identical with that of every other, a detail description of but one of these cylinders only is necessary.

Broadly considered, notwithstanding the particular adaptability of the invention to printing machines employing a plurality of plate cylinders, the detailed construction of the cylinder adapts it for use upon a machine employing but one plate cylinder.

The construction of the plate cylinder is such that while a plurality of plate carrying sections are employed, all of said sections will be rotated from a single source of power so as to ensure accuracy in the timing of the cylinder as a whole with relation to the offset planographic cylinder 10. While various designs of cylinders may be made which will secure the result, I preferably construct the cylinder as shown in the accompanying drawings, reference being had particularly to Figs. 2 to 7 of the drawings.

In the construction shown, I employ a cylinder having two sections 17 and 18, one of which, as 17, is provided with a reduced bearing portion 19 adapted to have idly mounted thereon the spur gear 20, which is in mesh with a spur gear 21 carried by the cylinder 10. A portion of the section 17 is recessed as indicated at 22, the rest of the surface being truly cylindrical, as shown at 23, so as to form a proper backing for the zinc, aluminum, or other plate to be carried by the cylinder. Within the re-

cessed portion 22, I provide suitable plate clamps 24 adapted to engage the opposite ends of the plate or sheet, this recessed portion also receiving the mechanism by means of which circumferential adjustment of the cylinder with relation to the gear 20 is effected. This adjusting mechanism, which will be more particularly referred to hereinafter, constitutes the sole means for transmitting power to the cylinder through the gears 20 and 21. The portions 22 and 23 extend for substantially one-half the length of the entire cylinder, the remaining portion of the cylinder being reduced as shown at 25 to form a bearing for the other cylinder section 18, the reduced bearing portion 25 being provided with oil grooves as shown, although if desired such may be dispensed with, and other means of lubrication provided.

The opposite ends of the cylinder are provided with reduced arbors 26 and 27 mounted in suitable bearings in the side frame of the machine, which bearings are of the usual and ordinary construction so that a detailed description thereof is unnecessary.

Secured in relation to, and so as to rotate with, the cylinder section 17 and the reduced portion 25 are circular end plates 28 and 29.

The section 18 is loosely mounted upon the reduced portion 25, being operatively connected therewith and with the section 17 in a manner to permit adjustment of the section 18 with relation to the section 17 both circumferentially and axially thereof, while at the same time ensuring simultaneous rotation of both cylinder sections with perfect timing as to each, through the gears 20 and 21.

The section 18 is provided with a recessed portion 31 corresponding with the recessed portion 22 and a truly cylindrical portion 32 corresponding with the cylindrical portion 2 of said section 17, and within the recessed portion 31 are plate clamps 33 corresponding with the clamps 24. In fact the sections 17 and 18, as to their outside dimensions and plate clamp construction, are identical one with the other, thus facilitating the makeready of the press to secure equally strong impressions from both cylinder sections.

Extending about the end of the section 17 throughout the cylindrical portion thereof is a recess 34 adapted to receive a bearing portion 35 carried by the section 18 to assist in securing and maintaining the alignment of the two sections 17 and 18.

The reduced portion 25 is provided with a plurality of circumferential grooves 36 adapted to receive set screws 37 which also serve as bearing caps for introducing oil between said reduced portion 25 and the

cylinder section 18, said grooves 36 having sufficient width to permit movement of the section 18 axially of the portion 25.

The cylinder section 17 and its appurtenances are connected with the gear 20 by means of studs 38 and 39 carried by said gear and passing through elongated openings in the end plate 28. Carried by the cylinder section 17 within the recess 22 thereof, is a low pitched screw 40, the opposite ends of which are tapered at 41 and 42 as shown, this screw being of a length to constantly engage the tapered end 41 with the stud 38, and the tapered end 42 with the stud 39, the screw 40 being adjustably mounted in a screw-threaded block 43 carried by the cylinder section 17. The screw 40 is provided with a portion 44 adapted to receive a spanner wrench or other suitable tool for actuating said screw. This, however, is a mere detail, since any desired means may be provided to facilitate the application of power to said screw.

The end plate 29 is provided with studs 45 and 46 similar to the studs 38 and 39, cooperating with which is a screw 47 having tapered ends 48 and 49 engaging the studs 45 and 46 in the same manner as the tapered ends 41 and 42 engage the studs 38 and 39, the screw 47 being mounted in a screw-threaded block 50 similar to the block 43, and having a portion 51 corresponding with the portion 44 of the screw 40. In this manner the cylinder section 18 is operatively connected with the cylinder section 17, and therethrough with the gear 20, and is yet capable of circumferential adjustment independently of said section 17 and said gear.

The set screws 37 are a mere precautionary expedient to avoid possible loss of adjustment when the cylinder section 18 has once been set for register with the section 17.

Idly mounted upon a reduced bearing adjacent the arbor 27 is a gear wheel 52 in mesh with a gear wheel 53 upon the cylinder 10, this gear 52 having no operative relation to the plate cylinder but serving to transmit power from said cylinder 10 to the inking mechanisms associated with said cylinder.

While the bolts for securing the end plates 28 and 29 to the cylinder section 17 and its reduced portion 25 pass through the gears 20 and 52 respectively, elongated segmental slots are provided in these gears to receive said bolts so that no movement is transmitted to the cylinder through said bolts.

The bolts referred to are shown at 54 and 55 respectively and merely serve to ensure exactitude in the centering of the plate cylinder with relation to said gears.

It must be borne in mind that in mounting the plates upon the cylinder, it is always possible to obtain fairly accurate register, and that the mechanisms for adjusting the plate

cylinder sections with relation to the driving gear 20 and each other, is used merely to correct very slight imperfections in register so that the movement of these sections required when adjusting for register, is very minute, requiring merely a slight clearance between said bolts and the gears, which condition applies to clearance provided in other parts of the mechanism.

I have heretofore described mechanisms by means of which the section 17 may be circumferentially adjusted, and the section 18 may be circumferentially adjusted independently of, but with relation to said cylinder section 17. The first, named mechanism is used exclusively for registering the plates upon one plate cylinder with the plates upon other plate cylinders, and will result in a similar actuation of both sections 17 and 18, while the latter mechanism is used exclusively for adjusting the section 18 for register with relation to the section 17, this adjustment being circumferential.

It is necessary, however, to provide means whereby the section 18 may be adjusted axially thereof for the purpose of securing lateral register of the plate thereon, with relation to the plate upon the section 17, and to provide means which will simultaneously move both sections 17 and 18 axially of the cylinder for the purpose of effecting lateral register of the plates upon both sections with plates upon other cylinders.

To permit axial adjustment for register of the section 18 with relation to the section 17, it is necessary that these sections be spaced apart slightly at their adjacent ends, and that these sections be connected in a manner which will not interfere with circumferential movement of the section 18 with relation to the section 17, which connection may be so actuated as to move said section 17 axially thereof toward or from said section 17.

The connections above referred to consist of a link 56 having a screw-threaded end mounted in a screw-threaded block 57 in one of said sections, as 18, the other end of which is provided with a grooved head 58 entering an elongated segmental slot in a block 59 carried by the other section, as 17, said link 56 being provided with a portion as the hexagonal section 60 by means of which it may be engaged by a suitable tool. I preferably provide the link 56 with a reduced screw-threaded end adapted to receive a lock nut 61.

To permit simultaneous axial adjustment of both sections 17 and 18, clearance between the cylinder and the side frame of the machine is provided, and means are provided whereby movement may be imparted to the cylinder to the extent of this clearance and axially of the cylinder. This means comprises in the form of the invention shown, an adjusting screw 62 carried by the bracket

63 extending across the arbor 27 of the cylinder, and bearing against the end of this arbor. The end of the arbor 26 is reduced at 64, said reduced end passing through a bracket 65, a coiled spring 66 bearing against said bracket, and the end of the arbor 26, being provided to normally thrust the cylinder in its entirety toward the adjusting screw 62. Said spring 66 encircles the reduced end of the arbor as shown more particularly in Fig. 2 of the drawings.

A detail construction of the clamp mechanisms 24 and 33 is immaterial to the present invention, which relates more particularly to a construction by which adjustment for register may be had entirely independently of this clamp mechanism.

The parts 67 are merely dust rings.

The operation of the herein described mechanism is substantially as follows:

An acid etched plate containing a design or a complementary portion of a design, or a repetition of such, the lines thereof being cameo lines when used with a multiple cylinder multicolor press, is mounted by means of the clamps 24 upon the cylinder section 17, said clamps 24 being used to accurately position this plate upon said sections. The design, or portions thereof upon this plate are to appear upon one side of a printed sheet only. When this plate has been properly mounted upon the cylinder section, a similar plate bearing a design, or a complementary portion of a design, or a repetition of such, is mounted by means of the clamps 33 upon the cylinder section 18, and the plate accurately positioned upon said section by means of the clamps. The designs upon the plate mounted upon the section 18 are to appear upon the reverse side of a completed sheet.

When these plates have been thus mounted upon the cylinder, a waste sheet is run through the press to make an imprint first on one side and then on the other side thereof, this waste sheet being carefully inspected to see that the back and front designs are in exact register one with the other. If it be found that the designs are out of register, the screw 47 is turned one way or the other to correct any such imperfections in register as can be corrected by circumferential adjustment of the plate, the turning of this screw through the engagement of the tapered points 48-49 thereof with the studs 45-46 imparting rotary movement to the section 18 about the cylindrical portion 25 of the section 17 in a direction determined by the direction in which said screw is turned.

By using a low pitched thread upon the screw 47, and a fairly high pitch of the tapered ends 48-49, a micrometrical adjustment of said cylinder section may be secured, as this construction provides a reducing ef-

fect in the wedging action exerted upon the 65 studs 45-46.

If the loss of register be axially of the cylinder, the section 18 may be moved toward or from the section 17 by means of the screw-threaded link 56, it being essential to 70 exercise considerable skill in actuating this link, since the sole reducing mechanism is the screw threads thereon co-operating with the screw-threaded block 57.

When the cylinder section 18 has been so 75 adjusted as to absolutely register the design or designs thereon with the design or designs upon the plate upon the cylinder section 17, the set screws 37 may be tightened to check any tendency of vibration interfering with 80 the adjustment of said section 18, although the likelihood of such occurring is very remote when the connection between the cylinder section 18 and the section 17 consists of the double pointed screw co-operating with 85 the studs 45-46 carried by the end plate 29. When the adjustment for longitudinal register has been secured by means of the link 56, the tightening of the lock nut 61 will preserve this relation. 90

As heretofore pointed out, the elongated slots in the block 59 and in the gear 52 will permit circumferential movement to that small extent necessary to correct imperfect register. When the parts have once been 95 adjusted and set as described, the cylinder section 18 will be firmly secured to, and will thereafter rotate with, the section 17, thus causing both sections of the cylinder to act as a unit. The plates upon one section thereof bear a design or a complementary portion or portions of a design for the imprint upon one side of the sheet, and the plates upon the other section thereof bear a design or a complementary portion or portions of a design for the imprint on the reverse side 100 of the sheet, both of which imprints will be made at a single impression so that by merely turning the sheet and feeding it again through the press, the front designs 110 will be impressed in exact register with the previously impressed back designs upon one portion of the sheet and the back designs will be impressed in exact register with the previously impressed designs for the front 115 of the sheet.

By using two plates, one bearing the design for the front of a completed sheet, and the other bearing a design for the back of the completed sheet, and by mounting both 120 these plates upon the same cylinder, absolute register of the back and front designs may be secured through a comparative adjustment of the plates upon the cylinder. In this manner accuracy of register is secured through mechanisms in the machine, as distinguished from the old methods wherein a high degree of skill was required to accu- 125

6
rately position the designs upon the different plates and adjustment for register can be secured only by shifting a plate in its entirety upon the cylinder by means of the 5 plate clamps.

10 While in adjusting the cylinder section 18 an imprint may be relied upon, it is apparent that actual measurements may also be made to secure accuracy in the relative positioning of designs upon different plates.

15 In multicolor presses in which the plates upon the cylinders 12, 13, 14 and 15 may bear complementary portions of the same design, the plates upon each cylinder are 20 adjusted for register in the manner above described, and when proper register has once been secured between plates upon the same cylinder, the respective cylinders 12 to 15 may be adjusted circumferentially of 25 the machine by means of the screw 40 co-operating with the studs 38 and 39, this adjustment being with relation to the gear 20 which has a fixed relation to the gear 21 carried by the cylinder 10. Adjustment by means of the screw 40 will cause similar circumferential adjustment of both sections 17 and 18, it being essential that said sections shall be capable of uniform similar adjustment for securing register of plates upon different cylinders.

30 If it is necessary to adjust any plate cylinder axially thereof to secure register, this is done by means of the adjusting screw 62 which acts against the tension of the spring 66, this adjustment being of the cylinder in its entirety.

35 By constructing all of the cylinders in the manner described, absolute register of the back and front designs may be secured by a 40 comparative adjustment of two plates bearing said designs respectively, and making impressions from said plates simultaneously, and complementary portions of each design upon different plates may also be 45 brought into absolute register by an adjusting mechanism acting similarly and simultaneously upon both plates upon each cylinder.

50 While I have referred herein to the work done as non-perfected work, I wish it to be understood that the same condition applies where the impression cylinder 10 is used as a printing cylinder, since it is essential, even though impressions be made 55 upon both sides of the sheet at the same time, that each sheet be run twice through the machine to secure a completed perfected impression.

60 The essential characteristic of the invention resides in a construction by which, at a single impression, a back design and a front design will be simultaneously impressed upon different portions of a sheet in such relation to each other that upon reversing the sheet, similar impressions will be

65 made upon different parts of the sheet, all of the designs, irrespective of their dissimilitude, being in exact register, so that when a repetition of designs is provided on each plate, the cutting of the sheet in the finishing room, will result in an even margin being present upon both sides of the sheet, thus making counterfeiting of all security paper more difficult, and detection thereof 70 easy, because of a readily discernible absence of register in the designs upon opposite sides of the sheet.

75 It is not my intention to limit the invention to the precise details of construction shown in the accompanying drawings, it 80 being apparent that such may be varied without departing from the spirit and scope of the invention.

85 Having described the invention, what I claim as new and desire to have protected by Letters Patent, is:—

90 1. A printing machine embodying therein a plate cylinder having a plurality of independently movable sections, means carried by each of said sections whereby a plate 95 may be secured thereto, co-operating members carried by and connecting adjacent sections to cause them to rotate in unison, one of said members including therein means whereby it may be actuated to impart to one of said sections circumferential movement in relation to the adjoining section to cause said section to be adjusted circumferentially of the axis of the cylinder entirely independently of another, and means whereby all of said sections may be simultaneously rotated.

100 2. A printing machine embodying therein a plate cylinder having a plurality of independently movable sections, means carried by each of said sections whereby a plate 105 may be secured thereto, co-operating members carried by and connecting adjacent sections to cause them to rotate in unison, one of said members including therein means whereby it may be actuated to impart to one of said sections circumferential movement in relation to the adjoining section to cause said section to be adjusted circumferentially of the axis of the cylinder entirely independently of another, means whereby one of said sections may be adjusted axially of the cylinder toward or from the other section, and means whereby all of said sections may be simultaneously 110 rotated.

115 3. A printing machine embodying therein a plate cylinder having a plurality of independently movable sections, means carried by each of said sections whereby a plate 120 may be secured thereto, co-operating members carried by and connecting adjacent sections to cause them to rotate in unison, one of said members including therein means whereby it may be actuated to impart to 125

one of said sections circumferential movement in relation to the adjoining section to cause said section to be adjusted circumferentially of the axis of the cylinder entirely independently of another, means whereby all of said sections may be simultaneously rotated, and means whereby all of said sections may be simultaneously and similarly adjusted circumferentially of said last named means.

4. A printing machine embodying therein a plate cylinder having a plurality of independently movable sections, means carried by each of said sections whereby a plate may be secured thereto, means whereby one of said sections may be adjusted circumferentially of the axis of the cylinder entirely independently of another, means whereby all of said sections may be simultaneously rotated, and means whereby all of said sections may be simultaneously and similarly adjusted axially thereof.

5. A printing machine embodying therein a plate cylinder having a section provided with a reduced bearing portion, a second cylinder section loosely mounted upon said bearing portion, co-operating means carried by said sections whereby said second section may be rotated with, or circumferentially adjusted independently of, said other section, means carried by each of said sections whereby a plate may be secured thereto, and means whereby power may be applied to said first named section to rotate said cylinder in its entirety.

6. A printing machine embodying therein a plate cylinder having a section provided with a reduced bearing portion, a second cylinder section loosely mounted upon said bearing portion, co-operating means carried by said sections whereby said second section may be rotated with, or circumferentially adjusted independently of, said other section, means carried by each of said sections whereby a plate may be secured thereto, operative connections between said sections whereby the section mounted upon said bearing portion may be adjusted toward or from said other section, and means whereby power may be applied to said first named section to rotate said cylinder in its entirety.

7. A printing machine embodying therein a plate cylinder having a plurality of independently movable sections, means carried by each of said sections whereby a plate may be secured thereto, co-operating members carried by and connecting adjacent sections to cause them to rotate in unison, one of said members including therein means whereby it may be actuated to impart to one of said sections circumferential movement in relation to the adjoining section to cause said section to be adjusted circumferentially of the axis of the cylinder entirely

independently of another, a driving gear, and operative connections between said gear and said cylinder.

8. A printing machine embodying therein a plate cylinder having a section provided with a reduced bearing portion, a second cylinder section loosely mounted upon said bearing portion, co-operating means carried by said sections whereby said second section may be rotated with, or circumferentially adjusted independently of, said other section, means carried by each of said sections whereby a plate may be secured thereto, a driving gear, and operative connections between said gear and said cylinder.

9. A printing machine embodying therein a plate cylinder having a section provided with a reduced bearing portion, a second cylinder section loosely mounted upon said bearing portion, co-operating means carried by said sections whereby said second section may be rotated with, or circumferentially adjusted independently of, said other section, means carried by each of said sections whereby a plate may be secured thereto, operative connections between said sections whereby the section mounted upon said bearing portion may be adjusted toward or from said other section, a driving gear, and operative connections between said gear and said cylinder.

10. A printing machine embodying therein a plate cylinder having a plurality of independently movable sections, means carried by each of said sections whereby a plate may be secured thereto, means whereby one of said sections may be adjusted circumferentially of the axis of the cylinder entirely independently of another, a driving gear, and operative connections between said gear and said cylinder, including therein adjustable means whereby circumferential movement may be imparted to said cylinder independently of said gear.

11. A printing machine embodying therein a plate cylinder having a plurality of independently movable sections, means carried by each of said sections whereby a plate may be secured thereto, means whereby one of said sections may be adjusted circumferentially of the axis of the cylinder entirely independently of another, a driving gear, operative connections between said gear and said cylinder, and means whereby said cylinder in its entirety may be adjusted axially thereof.

12. A printing machine embodying therein a plate cylinder having a plurality of independently movable sections, means carried by each of said sections whereby a plate may be secured thereto, means whereby one of said sections may be adjusted circumferentially of the axis of the cylinder entirely independently of another, a driving gear, op-

operative connections between said gear, and said cylinder, including therein adjustable means whereby circumferential movement may be imparted to said cylinder independently of said gear, and means whereby said cylinder in its entirety may be adjusted axially thereof.

13. A printing machine embodying therein a plate cylinder having a section provided with a reduced bearing portion, an end plate for said bearing portion, studs carried thereby, a second cylinder section loosely mounted upon said bearing portion, a screw having its opposite ends tapered and mounted in a screw-threaded block carried by said last named section with the tapered ends of said screw engaging said studs respectively, whereby said second section is operatively connected with said first named section, but may be circumferentially adjusted independently thereof, means carried by each of said sections whereby a plate may be secured thereto, and means whereby power may be applied to said first named section to rotate said cylinder in its entirety.

14. A printing machine embodying therein a plate cylinder having a section provided with a reduced bearing portion, an end plate for said bearing portion, studs carried thereby, a second cylinder section loosely mounted upon said bearing portion, a screw having its opposite ends tapered and mounted in a screw-threaded block carried by said last named section with the tapered ends of said screw engaging said studs respectively, whereby said second section is operatively connected with said first named section, but may be circumferentially adjusted independently thereof, means carried by each of said sections whereby a plate may be secured thereto, a driving gear idly mounted in relation to said cylinder, studs carried thereby, a screw having its opposite ends tapered, and a bearing block carried by said first named section in which said screw is mounted with its tapered ends engaging said studs respectively, whereby power may be applied through said first named section to said cylinder in its entirety and said cylinder may be circumferentially adjusted with relation to said driving gear.

15. A printing machine embodying therein a plate cylinder having a plurality of independently movable sections, means carried by each of said sections whereby a plate may be secured thereto, means whereby one of said sections may be adjusted circumferentially of the axis of the cylinder entirely independently of another, a screw-threaded block carried by one of said sections, a slotted block carried by the other of said sections, a screw-threaded link adjustably mounted in said first named block and having a grooved head co-operating with said first named block, whereby said adjustable

section may have axial movement imparted thereto toward or from the other section, the slot in said block being elongated to permit said circumferential movement, and means whereby all of said sections may be simultaneously rotated.

16. A printing machine embodying therein a plate cylinder having a section provided with a reduced bearing portion, an end plate for said bearing portion, studs carried thereby, a second cylinder section loosely mounted upon said bearing portion, a screw having its opposite ends tapered and mounted in a screw-threaded block carried by said last named section with the tapered ends of said screw engaging said studs respectively, whereby said second section is operatively connected with said first named section, but may be circumferentially adjusted independently thereof, means carried by each of said sections whereby a plate may be secured thereto, a screw-threaded block carried by one of said sections, a slotted block carried by the other of said sections, a screw-threaded link adjustably mounted in said first named block and having a grooved head co-operating with said slotted block, whereby said adjustable section may have axial movement imparted thereto toward or from the other section, the slot in said block being elongated to permit said circumferential movement, and means whereby power may be applied to said first named section to rotate said cylinder in its entirety.

17. A printing machine embodying therein a plate cylinder having a section provided with a reduced bearing portion, an end plate for said bearing portion, studs carried thereby, a second cylinder section loosely mounted upon said bearing portion, a screw having its opposite ends tapered and mounted in a screw-threaded block carried by said last named section with the tapered ends of said screw engaging said studs respectively, whereby said second section is operatively connected with said first named section, but may be circumferentially adjusted independently thereof, means carried by each of said sections whereby a plate may be secured thereto, a screw-threaded block carried by one of said sections, a slotted block carried by the other of said sections, a screw-threaded link adjustably mounted in said first named block and having a grooved head co-operating with said slotted block, whereby said adjustable section may have axial movement imparted thereto toward or from the other section, the slot in said block being elongated to permit said circumferential movement, set screws carried by said section mounted upon said bearing portion, and adapted to engage said bearing portion, and means whereby power may be applied to said first named

section to rotate said cylinder in its entirety.

18. A printing machine embodying there-in a printing couple including therein a cylinder having an offset planographic surface thereon, a plurality of plate cylinders grouped about said cylinder having the planographic offset surface, each of said cylinders embodying therein a plurality of sections, means carried by each of said sections whereby a plate may be mounted thereon, and means whereby one of said sections may be adjusted with relation to the other to bring the designs upon each of said plates 10 in register with the designs upon the other plate, a gear carried by said cylinder having the planographic offset surface, a gear idly mounted in relation to each of said cylinders and meshing with said first named gear, operative connections between each of 15 20

said last named gears and its associated plate cylinder, whereby said plate cylinders respectively may be circumferentially adjusted with relation to their associated gears, and means whereby each of said cylinders 25 may be adjusted axially thereof, said last named circumferential and axial adjustment permitting the plates upon each of said plate cylinders to be brought into register with the plates upon the other of said plate 30 cylinders.

In witness whereof I have hereunto affixed my signature, in the presence of two subscribing witnesses, this 27th day of February, 1922.

FRANK C. MARQUARDT.
